UNITED STATES PATENT OFFICE.

TOLLAK TOLLEFSON, OF BONILLA, SOUTH DAKOTA.

MAIL-BOX BRACKET.

Application filed November 20, 1922. Serial No. 601,966.

To all whom it may concern:

Be it known that I, TOLLAK TOLLEFSON, a citizen of the United States, residing at Bonilla, in the county of Beadle and State 5 of South Dakota, have invented certain new and useful Improvements in Mail-Box Brackets; and I do hereby declare the following to be a full, clear, and exact description of the invention, such as will enable 10 others skilled in the art to which it appertains to make and use the same.

This invention relates to a support particularly adapted to be used with a mail box. As is well known, mail boxes are now 15 used in the rural districts in connection with the rural free delivery mail service and such boxes are usually secured to posts or other members disposed along the side of the road. The mail carrier uses some sort 20 of vehicle in delivering the mail and the boxes are usually disposed so that they can reach the same without leaving such vehicle. Most roads have a decided downward inclination at the side thereof and are often 25 provided with a ditch along such side. When the roads are wet or slippery it frequently happens that the mail carrier's vehicle slides down the inclined side of the road and becomes jammed against or otherwise 30 caught on the mail box post and support, thus causing delay and difficulty. It also frequently happens that teams, hayracks, etc., in passing get sufficiently on the 35 side of the road to run against the mail boxes which are thus often torn loose or damaged.

It is an object of this invention to support a mail box in such a manner that it 40 will normally occupy a position extending outward toward the road but can be swung to one side or to the other after which it will return to its normal position automatically.

It is a further object of the invention to 45 provide such a supporting means comprising a bracket carrying a mail box upon its outer end and being pivoted at its inner end on an axis which is inclined outwardly to the vertical toward its upper end.

It is more specifically an object of the 50 invention to provide such a bracket having spaced arms at its inner end which are journaled on a pintle which inclines outwardly of its supporting means toward its upper end.

These and other objects and advantages of

the invention will be fully set forth in the following description made in connection with the accompanying drawings in which like reference characters refer to the same 60 parts throughout the different views, and in which,

Fig. 1 is a view in side elevation of the mail box support showing the box and supporting post in connection therewith; and 65

Fig. 2 is a view in front elevation of said parts showing the box in lateral positions in dotted lines.

Referring to the drawings, a diagrammatic cross section of the road is shown 70 at 1 and at one side thereof, a supporting post 2. A supporting bracket is provided and has a substantially vertical side 3 secured to post 2 by bolts or suitable screws and said bracket has arms 4 and 5 extending 75 outwardly toward the road and also inclined somewhat downwardly, said arms having flat surfaces at their upper sides. A swinging bracket 6 is provided adapted to have a mail box 7 secured thereto at 80 its outer end and said bracket has spaced arms 8 and 9 extending at its inner side having the inner ends bent at a right angle so as to be disposed upon the arms 4 and 5. A headed and nutted pintle bolt member 85 10 extends through the arms 8 and 9 and arms 4 and 5 so that the arms 8 and 9 are journaled thereon.

The supporting bracket secured to the post and the swinging bracket carrying the 90 mail box are conveniently and preferably made from flat bars which can also be provided with the necessary attaching and assembling holes.

Owing to the pintle member 10 being inclined outwardly to the vertical toward its upper end, when the swinging arm 6 is swung laterally thereon it will be elevated or moved to a tilted position, as shown by the dotted lines in Fig. 2 and will swing 100 by gravity back again to the position shown in Fig. 1 and partially shown in full lines in Fig. 2. By so mounting the mail box, the same will extend sufficiently outward over the road so that the mail man will 105 not have to drive down along the inclined side of the road or into the ditch in order to reach the same. Furthermore, if any vehicles get sufficiently off the road to strike the mail box the same will simply be swung 110 laterally and allow the passage of such vehicle after which the box will again swing

to its normal outwardly extending position.

From the above description is it seen that applicant has provided an extremely simple and efficient mail box support. The device 5 will have greater utility in supporting the mail boxes now used in rural communities.

It will, of course, be understood that various changes may be made in the form, details and operation of the device without 10 departing from the scope of applicant's invention, which, generally stated, consists in the matter shown and described and set forth in the appended claims.

What is claimed is:

15 1. A mail box structure comprising a support, a bracket rigidly secured thereto in a vertical position having outwardly pro-

jecting vertically spaced arms, the upper arm being longer than the lower arm, a rotatable spindle journaled in said arms and 20 inclining outwardly from its bottom to its top, a swinging bracket having spaced arms journaled on said spindle and normally projecting outward from said support in substantial alignment with said first mentioned bracket and arms but movable laterally into a higher plane at either side of 25 said normal position about the axis of said spindle.

2. The structure set forth in claim 1, the 30 arms of said swinging bracket resting on the arms of said first mentioned bracket.

In testimony whereof I affix my signature.
TOLLAK TOLLEFSON.
